UNITED STATES PATENT OFFICE.

CHARLES FREBORG, OF KANKAKEE, ILLINOIS, ASSIGNOR TO SCHAEFFER PIANO MFG. COMPANY, A CORPORATION OF ILLINOIS.

PNEUMATIC PIANO-PLAYER.

1,205,727.

Specification of Letters Patent. Patented Nov. 21, 1916.

Application filed July 28, 1911. Serial No. 641,133.

To all whom it may concern:

Be it known that I, CHARLES FREBORG, a citizen of the United States, residing at Kankakee, in the county of Kankakee and 5 State of Illinois, have invented certain new and useful Improvements in Pneumatic Piano-Players, of which the following is a specification.

My invention relates to automatic piano 10 players and has particular reference to improved supports for the pneumatics which operate the stickers in the piano action. These supports are adapted to guide the pneumatics into their proper positions in 15 assembling, in which positions they have the proper operative relation to said stickers. These supports are self-locking in said positions.

By means of my improvement above de- 20 scribed the entire group of pneumatics in an instrument may be removed or replaced with the utmost facility. When thus removed the action is entirely accessible.

My invention also comprises an improved 25 method of mounting the pneumatics themselves in said supports. The pneumatics are arranged in a plurality of horizontal rows immediately in front of the stickers, and each pneumatic is therefore very ac- 30 cessible from the front of the instrument. The said pneumatics are so arranged as to be adjustable in horizontal directions and also in vertical planes, thereby permitting accurate operative connections to be made 35 with the stickers.

I have also made certain improvements in the valves and other connections in which the air which operates the pneumatics is controlled.

40 Other objects and advantages of my improvements will appear in the following specification, when taken in connection with the accompanying drawings, in which—

Figure 1 is a vertical section through the 45 upper portion of an instrument with my improvements attached. Fig. 2 is a front elevation of the same with portions broken away. Fig. 3 is an enlarged vertical section of a portion of the mechanism shown 50 in Fig. 1, showing more particularly the

vacuum chamber and related parts. Fig. 4 is a perspective view of the base which serves as a guiding and locking device for the pneumatic supports. Fig. 5 is a plan view of one of the pneumatics. Fig. 6 is a 55 sectional view through one of the adjustable exhausting apertures. Fig. 7 is a front elevation of some of the movable parts.

Referring to Figs. 1 and 2, it will be seen that a pair of supporting members 10 60 are employed for holding the series of pneumatics 12. These supporting members 10 rest upon base members 11 of a special form which will be referred to presently. The pneumatics 12 are arranged in three parallel horizontal rows directly in front of the stickers 13 of the piano action. Each row of pneumatics 12 is supported by a horizontal bar 14, which, in turn, is secured to the supporting members 10 at each of its 70 ends. A suitable socket 14^a in said supporting member receives the end of the bar, and a small screw 15 holds the said bar in said sockets. There are preferably three of these supporting bars 14 arranged in a vertical 75 plane, and the pneumatics 12 are attached thereto and have positions below them. They are rigidly secured to said bars by means of the clips 25, through which holding screws or set screws 26 are threaded and 80 which bear on said bars 14. By means of this method of securing the pneumatics to the bars the said pneumatics are made rotatably adjustable in vertical planes and their operative relation to the stickers 13 85 may be thereby accurately adjusted. This means of attachment also permits a horizontal adjustment of the pneumatics along the bars for like purposes.

The supporting members 10 are provided 90 with feet 16 and 17, which rest upon the sunken portions 18 of the base 11. One of these feet 17 is provided with a tapered end or toe 19, which is inserted beneath a lug 20. The other foot 16 is adapted to bear at 95 its end upon a shoulder 21 in said base 11 when the support is in its normal position.

The base 11 is provided with an inclined plane or guide-way 22, which is adapted to 100 guide said feet 16 and 17 into the normal

position above described. The purpose of this inclined guide-way 22 is to cause the supporting member 10 to assume an inclined position while it is sliding into its normal position. The small lifting arms 23^a are thereby caused to move into position well below the little brackets 23 on the stickers 13. When the supporting members 10 finally reach the sunken portions 18, they then assume an upright position bringing the said arms 23^a into operative contact with the little brackets 23. The shoulder 21 constitutes an abutment to lock the supporting member 10 in its normal operative position. The base members 11 are each provided with a flange 24 upon their inner sides or walls, thereby causing the supports to be properly positioned laterally.

Each of the pneumatics 12 is connected 20 with a vacuum chamber 28 and valve mechanism associated therewith by means of the flexible tubes 27. The vacuum chamber 28 is supported by the supporting members 10 at 30 and 31. The vacuum chamber is constructed preferably of wood, as shown at 29, it being an elongated box-like receptacle resting at its ends upon the said supporting members 10.

The supporting members 10 are provided 30 with upwardly extending arms 34, which are rigidly secured to the frame 35 of the instrument by means of the short connecting bars 32. The thumb screws 33 serve to make the connection between the said arms 34 and bars 32. The rear ends of the bars 32 may be threaded into the frame member 35, or otherwise secured thereto. It will be seen that the connection at 33 may be made after the lower ends of the supports 10 have 40 reached final or normal positions, at which time the said supports assume upright positions, as previously described. Thumb screws 36 may serve to hold the vacuum chamber 29 upon the said supports. A valve chamber 37 is provided in the upper wall 45 of said vacuum chamber. In this vacuum chamber are two circular or disk valves 40 and 41, which are secured to a stem 41^a and which are adapted to move in opposite directions toward their respective seats. These valves control oppositely extending air passages 38 and 39, respectively. The air passage 38 leads to the open air, while the passage 39 leads to the vacuum chamber 28. 50 These valves are actuated by a small bellows 42 secured to the lower wall of the vacuum chamber 29. The upper or movable portion of said bellows actuates the valve stem 41^a when air is admitted to the interior of said bellows through the channel 43. Air is admitted to the channel 43 through the small channel 44, which communicates with a tube 45 leading from the tracker board 46. A small channel 47 leads laterally from the

channel 44 and is opened to a channel 48 in 65 a tube or bushing 48^a, which is tightly secured in the upper wall of the vacuum chamber. A small channel 51 leads from said chamber 49 into the vacuum chamber 28. A threaded stem or needle valve 52 is fitted 70 into said bushing 48^a and is provided with the conical end 53 which seats in the upper end of the channel 51. A small chamber 49 is thereby formed between the valve end and its seat. The threaded valve 52 is preferably 75 tightly fitted in the bushing 48^a. The escape of the air is thereby prevented. The conical end may be adjusted to a greater or less closeness to the seat, thereby controlling the extent of opening between the chamber 49 80 and said channel. The valve 52 may be adjusted by means of an ordinary screw driver applied at 54.

The above described needle valves 52 serve as a very convenient adjustable means for 85 controlling what may be termed exhausting apertures. These apertures lead from the tube 45 and channels 43 and 44 into the vacuum chamber, thereby allowing the air in said chamber to be released.

The small needle valves 52 are arranged 90 in a horizontal row adjacent the upper edge of the vacuum chamber, and are therefore in a very accessible position. All of the valves 40, 41 are also very accessible and may be removed by withdrawing the screw 55.

The music box 56 containing the music rolls and tracker board may be mounted upon the upper wall of the vacuum chamber 28 by means of standards 57 secured thereto. 100 In like manner the motor 58 may be supported. These parts are therefore all carried by the same supports 10 and base 11 and are very conveniently removed or replaced. Complete access to all parts of 105 the action is permitted by removing all of the parts carried upon the base 11. It is necessary only to remove two screws 33 to permit removal of said parts.

While I have described my invention more 110 or less minutely and as being embodied in certain precise forms, yet it will be understood that I do not desire to limit myself thereto unduly, or any more than is pointed out in the claims. On the contrary, I 115 contemplate changes in form, construction, and arrangement, the omission of parts, and the substitution of equivalents as circumstances may suggest or necessity render expedient.

I claim:

1. In a device of the character described, a series of piano stickers, a series of pneumatics arranged to coact with and operate said stickers, supporting bars, said pneumatics being attached thereto, supporting 125 means, said bars being carried thereby and said means being constructed and arranged to move the pneumatics into operative rela-

tion with the stickers when assembling said device, said means being further constructed to lock the pneumatics in such relation.

2. In a device of the character described, 5 a series of piano stickers, a series of adjustable pneumatics in operative relation to said stickers, and supporting means for said pneumatics adapted to guide said pneumatics into said operative relation and to 10 lock them in said position.

3. In a device of the character described, 15 a series of piano stickers, a plurality of rows of pneumatics in operative relation to said stickers, a separate supporting bar for each row, a standard to which said bars are fixed, a base and means on said base adapted to guide said standard into its normal position and to automatically lock said standard in said position.

20 4. In a device of the character described, a series of piano stickers, a plurality of rows of adjustable pneumatics in operative relation to said stickers, a separate supporting bar for each row, a standard to which said bars are fixed, a base, and means on said base adapted to guide said standard into its normal position and to lock said standard in said position.

25 5. In a device of the character described, 30 a series of piano stickers, a plurality of rows of pneumatics in operative relation to said stickers, a separate supporting bar for each row, a standard to which said bars are fixed, a base, and means on said base adapted to 35 guide said standard into its normal position and to lock said standard in said position, and means for securing the upper portion of said standard to the frame of the instrument.

40 6. In a device of the character described, a series of piano stickers, a series of pneumatics in operative relation to said stickers, supports for said pneumatics, means for guiding said supports into said relation and 45 means integral with said guiding means for engaging said supports when they reach said relation, whereby said pneumatics are rendered self adjusting and self locking.

7. In a device of the character described, 50 a series of piano stickers, a series of pneumatics arranged to operate said stickers, supports for said pneumatics, means to guide said supports into assembled position when assembling said device whereby said 55 pneumatics will be simultaneously brought to operative relation with respect to said stickers, said guiding means being constructed to automatically lock said supports and thereby said pneumatics in assembled 60 position.

8. In a device of the character described, a series of piano action stickers, actuating mechanism for said stickers, supporting means for said mechanism constructed to

guide said mechanism into operative relation to said stickers when assembling said device, and to lock the same in such relation. 65

9. In a device of the character described, 70 a series of piano action stickers, actuating mechanism for said stickers adjustable with relation thereto, supports for said mechanism adapted to guide said mechanism into operative relation to said stickers and to lock said mechanism in said position.

10. In a device of the character described, 75 a piano action, driving means for said action, and means for guiding said driving means into operative relation to said action, said guiding means having an abutment adapted to lock said driving means in said 80 operative relation.

11. In a device of the character described, 85 a piano action, driving means for said action, movable supports for said driving means, and means for guiding said supports into operative relation to said piano action, said guiding means having an abutment adapted to lock said supports.

12. In a device of the character described, 90 a piano action, driving means for said action, movable supports for said driving means, means for guiding said supports into operative relation to said piano action, said guiding means having an abutment adapted to lock said supports, and controlling mechanism for said driving means 95 carried by said supports.

13. In a device of the character described, 100 a series of piano stickers, a series of pneumatics in operative relation to said stickers, means for separately adjusting each pneumatic with relation to its respective sticker, 105 and supporting means for all said pneumatics adapted to guide all said pneumatics simultaneously into said operative relation.

14. In a device of the character described, 110 a series of piano stickers, a plurality of series of pneumatics in operative relation to said stickers, a plurality of supporting bars for said pneumatics, one for each series, a 115 standard to which said bars are fixed, and a base on which said standard rests having a guiding portion for causing said pneumatics to move into operative relation to said stickers and said base having a depressed portion into which said standard drops and by which it is locked in said position.

15. In a device of the character described, 120 a piano action, driving means for said action, and means for guiding said driving means into operative relation to said action, said guiding means having a depressed portion into which said driving means drops and by which it is locked in said position.

16. In a device of the class described, 125 a plurality of parallel bars supported at their ends, respective series of pneumatics ar-

ranged adjacent to each bar, the pneumatics of the different series being staggered, rings on the bars to which the respective pneumatics are attached, and means for adjusting the rings on said bars.

17. In a device of the class described, a series of pneumatics, supporting means for said pneumatics comprising a plurality of parallel bars, said pneumatics being at-

tached to said bars in such wise as to permit lateral adjustment and adjustment in a vertical plane relative thereto.

In testimony whereof, I have subscribed my name.

CHARLES FREBORG.
